Inventor

UNITED STATES PATENT OFFICE.

JOSEPH KLIMALA, OF CHICAGO, ILLINOIS.

AUTOMATIC RAILWAY-CROSSING GATE.

Application filed February 8, 1926. Serial No. 86,733.

The invention relates to automatic railway gates, the principal object thereof being to provide a gate capable of remaining in closed position by virtue of gravity.

- 5 Another object of the invention is to provide a gate of such a construction that it would be easily operable and where a slight actuation would bring it either to a closed or open position.
- 10 A still further object of the invention is to provide suitable mechanisms associated with rails which may be capable of operation by train for the purpose of closing and opening the gate.

15 With the above general objects in view and others that will appear as the nature of the invention is better understood, the same consists in the novel construction, combination and arrangement of parts hereinafter 20 more fully described, illustrated in the accompanying drawings and pointed out in the appended claims.

25 In the drawings forming a part of this application and in which like designating characters refer to corresponding parts throughout the several views,

Fig. 1 is a side elevational view of the gate with the mechanism associated with the rail for operating the gate;

30 Fig. 2 is a top view of a railway track showing the two gates, one at each side of the track, together with the mechanisms associated with one of the rails for operating the gate; and

35 Fig. 3 is a cross-sectional view through the mechanism for opening the gate, the view having been taken on line 3—3 of Fig. 1.

Referring to the construction of the device in detail, the gate, consisting of bottom section 10 weight 11 and brace 12 is pivotally mounted on pin 13 within the bifurcated upper end of post 14. As plainly seen on Fig. 1, brace 12 connects the lower section 10 with weight 11. The gate further comprises 40 a railing 15 which is adapted to be actuated by a mechanism hereinafter described for opening the gate. A similar railing 16 is provided at the opposite side of the gate co-operating with the mechanism for closing 45 the gate. Each of said railings is spaced away from the section 10 for receiving in the resulting spaces the bifurcated ends of post 14, as plainly seen on Fig. 2.

50 A gate of similar construction is positioned on the other side of track 17 and com-

prises weight 11' brace 12' bifurcated post 14', railing 15' for closing the gate, and railing 16' for opening the gate. Both gates are adapted for operating in unison by means of the mechanism hereinafter 55 described.

Referring now to the gate closing mechanism, the same comprises a rail section 18, which is positioned within the cutaway portion of the rail 19, and is held therewithin by 60 braces 20 which by their ends are secured to the adjacent ends of the rail, as at 21. The said rail section 18 is pivotally mounted within braces 20 at its end farther removed from the gate, the pivot point being indicated by 22. Block 23 is positioned directly below the rail section 18. Normally said block and the rail section 18 remain elevated by virtue of the coil spring 24 which remains interposed between block 23 and support 25. For guarding against the lateral displacement of the spring 24 said block 23 is provided with a cup 26 for receiving the upper end of said coil spring 24, and a similar cup is made in the support 25 for receiving the lower end of said spring. 70

Block 23 at the point substantially directly below the pivot point 22 of rail section 18 is provided with a depending projection 27 wherein rod 28 is rigidly mounted. At 75 its outer end rod 28 has a lever 29 keyed thereto. Horizontal link 30 is pivoted to said lever 29, and at its other end said link 30 is in pivotal association with lever 31 fulcrumed at 32. Pivots connected to the 80 lower end of said lever 31 is a rod 33. The opposite end of said rod 33 is pivotally connected to a downwardly depending projection 34 carried by ring 35 which is rigidly mounted upon rod 36. Keyed upon the near 85 end of rod 36 is a lever 37 which at its upper end carries a laterally projecting pin 38. Said pin carries a roller 39 which is adapted for sliding movement upon railing 16 of the 90 gate.

As shown on Fig. 2 the opposite end of rod 36 passing through the lower portion of post 14', as at 40, has a lever 37' which is adapted for sliding movement upon railing 16' of the gate at the other side of the 105 track 17.

It is observed that the two ends of the gates 12 and 12' have more or less equal weights at each of their ends, so that when they are brought to the closed position, illus- 110

trated on Figs. 1 and 2 they will remain in that position without any pressure being exerted thereupon by levers 37 and 37'.

For opening the gate a recess 42 is made in rail 19 at a point at the other side of the crossing. Rail section 43 is positioned within said recess and pivotally held therewith in by braces 45 which at their ends are secured to the adjacent ends of the rail as at 46 and 47. Below section 43, at the end opposite from the pivot 44 block 48 is positioned, which normally is at an upward pressure by coil spring 49 positioned within cup 50 by its upper end. The lower end of said spring 50 rests within plate 51. Said block 48 has a projection 52 wherein rod 53 is rigidly keyed. The end of said rod 53 carries lever 54 which is keyed to said rod 53. The upper end of said lever 54 is pivotally connected to one end of horizontal link 55. The other end of said link 55 pivotally connects to lever 56 which is fulcrumed at 57. To the lower end of said lever 57 one end of operating rod 58 is connected, while the other end of said operating rod 58 is in pivotal association with a downwardly depending projection 59 integrally formed with gate opening lever 60. The upper end of said lever 60 carries a pin 61 having a roller 62 positioned thereupon. Said roller is adapted to ride within depression 63 of the railing 15. Rod 64 passing through the lower portion of post 14, as plainly seen on Figs. 1 and 2, is by its one end keyed to lever 60 as at 65. The other end of said rod 64 is in rigid engagement with the lower end of lever 60' which is adapted to open the gate at the opposite side of the track 17. Said lever 60' carries a pin 61' having a roller 62' which is adapted for sliding movement within a depression 63' made in the railing 15'.

From the drawings and hereinabove description it will be apparent that rollers 62 and 62' are disposed upon railings 15 and 15', respectively, at one side of the pivot point 13 and 13', while levers 37 and 37' with their cooperating rollers 39 and 39', are disposed at the opposite side of said pivot point 13 and 13' respectively. It is to be further observed that levers 37 and 37' are intended to operate simultaneously and same holds true with the levers 60 and 60'.

The operation of the invention is as follows: Assuming the gate to be open, the position indicated by the dotted lines on Fig. 1 train 66 (Fig. 1) approaching the crossing and the gate will exert a downward pressure by wheel 67 upon rail section 18 causing downward movement of block 23 and a constant angular shifting of projection 27, which in turn will impart a rotary shifting movement to rod 28. Rod 28 will cause lever 29 to make an angular shifting

movement by its upper end and exert a pressure upon connecting link 30, which in turn will exert a pressure upon the upper end of lever 31. Said lever 31, by virtue of its permanent fulcrum point 32 will exert a pressure in the opposite direction upon operating rod 33, which by its other end will pull upon projection 34, in consequence whereof the upper end of lever 37 with its roller 39 will bear upon railing 16 and will cause the closing of the gate. Since both ends of the gate are more or less equal in weight, the gate brought to the closing position illustrated on Fig. 1 will remain in that position, notwithstanding the fact that the several wheels of the train passing over the track, fail to exert a continuous pressure upon section 18, even after the train completely passes section 18, and said section reverts to its original normal position by being pressed upwardly by spring 24, the gate will continue to remain in the closed position owing to its equilibrium until the train reaches the gate closing mechanism at the opposite side of the crossing. From the hereinabove description it will be seen that even the first wheel of the train or of the locomotive is sufficient to cause the operation of the gate closing mechanism for the purpose of bringing the gate to the closed position illustrated on Fig. 1.

The said gate opening mechanism hereinabove described is illustrated on Fig. 1 as being in a normal inoperative position. As soon as the train by its wheels comes over section 43 it will exert a pressure upon block 48, and by virtue of the construction hereinabove described, said block will cause an angular shifting movement of lever 54, the upper end of which lever will exert a pressure upon rod 55 in the direction of the gate. The other end of said rod 55 will exert a pressure upon the upper end of lever 56 in the same direction, causing the lower end of said lever 56 to shift in the opposite direction, thus exerting a pulling force upon operating rod 58 which in turn will pull upon the projection 59 which is integrally formed with lever 60. This force will cause the upper end of lever 60 with its roller 62 to shift toward the weight 11, or 11', as the case may be, and exert a downward pressure upon the respective end of the gate. This downward pressure of roller 62 will cause the opening of the gate. The opened gate will assume the position illustrated by dotted lines on Fig. 1.

Pins 68 and 68' are provided at the upper ends of post 14 and 14', respectively, which, bearing against railings 16 and 16', respectively, limit a further upward movement of the gate as plainly seen on Fig. 1.

Below one end of each gate buffers 69 are provided which act as shock absorbers during the opening of the gates as is obvious.

By virtue of the equilibrium of the gates, as hereinabove described, even a slight actuation of levers 60 and 60' will be sufficient to open the gates.

It is understood that in practice several parts of the invention hereinabove described should be covered or suitably housed as well as suitably anchored.

While there is described herein a preferred embodiment of the present invention it is nevertheless to be understood that minor changes may be made therein without departing from the spirit and scope of the invention as claimed.

What I claim as new is:—

1. A railroad crossing gate comprising a support, a swinging member pivoted in said support, said swinging member being adapted to assume open or closed position and being constructed to remain in either open or closed position by virtue of equilibrium, a lever associated with said swinging member for bringing the same from open to closed position, means cooperating with said track for actuating said lever, another lever associating with said swinging member for bringing the same from closed to open position, and means cooperating with the rail track for actuating the latter lever, both of said means being adapted for alternating operation by being actuated by the train wheels.

2. A railroad crossing gate comprising a support, a swinging member pivoted in said support, said swinging member being adapted to assume and remain in a horizontal or closed position by virtue of its equilibrium, a lever associating with said swinging member, a rail section in the adjacent rail, a spring under said rail section for normally maintaining said rail section in an elevated posi-

tion, said rail section being adapted to be actuated by the wheels of a passing train, and means cooperating with said lever and said rail section for actuating said lever on actuation of said rail section by the train wheels for bringing said swinging member to a closed position.

3. A railroad crossing gate comprising a support, a swinging member pivoted in said support, said swinging member being adapted to assume and maintain intermittently either open or closed position by virtue of its equilibrium, a lever associating with said swinging member for bringing the same from an open to a closed position, another lever associating with said swinging member for bringing the same from a closed to an open position, a rail section in the adjacent rail, a spring under said rail section normally maintaining said rail section in an elevated position, another rail section in the adjacent rail, a spring for normally maintaining the latter rail section in an elevated position, each of said rail sections being adapted for intermittent downward pressure by the train wheels against the tension of the respective springs, means between said first named lever and said first named rail section for imparting to said lever the motion of said rail section when pressed by the train wheels for actuating said swinging member into a closed position, and another means between said second named lever and said second named rail section for imparting to said second named lever the motion of said second named rail section when pressed by the train wheels for actuating said swinging member from a closed to an open position.

In testimony whereof I affix my signature.
JOSEPH KLIMALA.
